UNITED STATES PATENT OFFICE.

LESLIE MCHARG, OF FREEPORT, NEW YORK.

PIER DOOR.

Application filed August 30, 1921. Serial No. 496,801.

To all whom it may concern:

Be it known that I, LESLIE MCHARG, a citizen of the United States of America, residing at Freeport, in the county of Nassau and State of New York, have invented certain new and useful Improvements in Pier Doors, of which the following is a full, clear, and exact description.

In a patent granted to me on the 22nd of February, 1921, No. 1,369,425, I have shown and described an improved pier door composed of two sections, an upper and a lower, with means for raising the lower section until it completely overlaps the upper, and then raising both sections to fully open the door, by guiding both from a vertical into a horizontal position. Under ordinary conditions such as are met with in piers, freight warehouses and the like, the use of such double doors is necessary, but under certain other conditions this is a mere complication that may be avoided by the use of a single door section to accomplish all the desired results.

Single section doors for this purpose, however, may be required to be heavy and large, and without special provision to the contrary they will require much more head room over the door than is usually available for opening. Their mass and weight are so great as to need counterbalancing to obviate the expenditure of great force in raising them, and they must be always guided and restrained so as not to be capable of any lateral movement, otherwise they might blow open in a strong wind, or be forced into an inclined position by any weight or pressure applied to them.

To meet all the practicable requirements of such a door, I have devised a single section pier door with means for opening and closing the same, which embody the principle of the construction and operation of the doors of the patent above referred to but which means are so modified as to operate more easily and also to meet the conditions which prevail in the case of a single section, that are not met with in the case of two section doors, and this improvement I have illustrated in the present application and defined in the appended claims.

In the accompanying drawing,

Fig. 1 is a side view of my improved door; Fig. 2 is a section of the same on the line 2—2 of Fig. 1;

Fig. 3 is a view of the door in front elevation;

Fig. 4 is an enlarged detail view of the special lifting means.

The door is composed of a single section 1 of the usual form, dimensions and construction. Above it and to one side is a shaft 2 supported by brackets or hangers 8 with bearings carrying loosely mounted sleeves 11 in which the shaft 2 freely turns. To the shaft 2 is fixed a sprocket wheel 3 which is driven by a chain belt from a pinion sprocket 4 on a short shaft 5 which carries a chain sprocket 6 over which runs an endless engaging chain 7 by means of which rotary motion is imparted to the said shaft 5 and from that to shaft 2.

On the shaft 2 are keyed two fixed sheaves 9, and to the sleeves 11 are secured, as by set screws, two sheaves 10 which turn freely with said sleeves and about the shaft 2. Chains 12 are connected at one end to each edge or side of the door 1 near the bottom at 18 and at the other end to said edges at 17 at the middle of the door. These chains pass over both sheaves and around a third or idler sheave 13, from which are suspended weights 14, sufficient at all times to counterbalance the weight of the door.

The door at top and bottom on each side is provided with brackets 15 carrying rollers that travel in side guides 16. These guides are vertical to a point sufficiently above the normal position of the door, and are then properly curved into horizontal portions, so that as the door is raised it shifts from a vertical into a horizontal position, occupying substantially the position shown in dotted lines in Fig. 1 when fully opened.

When the door is to be opened the chain 7 is pulled by hand and the fixed sheaves 9, thus rotated. This raises the door and permits the weights 14 to descend. The weights pull up on the chain ends which are connected to the middle of the door as well as upon those ends connected to a point near the bottom, so that comparatively little force is required to turn the shaft 2 and its fixed pulleys. This counterbalancing effect continues until the door is fully opened, and the same force is exerted to close the door when the shaft 2 is rotated in the opposite direction.

In my previous construction the loose sheaves 10 were mounted directly on the shaft 2 and turned on that shaft as a bear-

ing. This I have found to be very objectionable, for no matter how perfectly the parts are constructed in practice it is found that the friction adds very materially to the amount of applied force necessary to operate the door, and interferes in other ways with its use. By using the sleeves 11, which turn freely in the hangers 8 and which afford bearings for the shaft 2, these objections are entirely avoided and much better results are secured.

This is an extremely simple, but a most effective device, and meets a want which has long existed in the ready and easy operation of doors of this character. In fact with the means and methods heretofore in use for this purpose, it was either necessary to apply great force to overcome friction and the weight of the door or to use devices of too complicated and expensive a nature to permit of their general or extensive use.

What I claim is:—

1. The combination with a pier door, of a shaft with means for rotating the same for opening or closing the door, sleeves rotatably mounted in stationary bearings and affording the bearings in which the shaft turns, two sheaves fixed to the shaft, two sheaves fixed to the sleeves, chains running over said sheaves and connected at their

ends to the bottom and middle points of the sides of the door, idler sheaves carried by the chains, counterbalancing weights suspended from said idler sheaves and guides for said door by which it is shifted when rising from a vertical to a horizontal position. 35

2. The combination with a single section pier door, of a shaft above and to one side of the same, means for rotating said shaft when the door is to be opened or closed, two sleeves rotatably mounted in stationary bearings through which the said shaft passes and freely turns, two sheaves keyed to the ends of the shaft, two sheaves fixed to the ends of the sleeves projecting from the stationary bearings, chains running over both sheaves and connected to the single section at the bottom and middle points, idler sheaves carried by the chains, counterbalancing weights suspended from the idler sheaves and guides for said door by which its upper edge is carried from the vertical to the horizontal portion of said guides and the door thereby shifted, when raised from a vertical to a horizontal position. 40 45 50 55

In testimony whereof I hereto affix my signature.

LESLIE McHARG.
